COIN CONTROL MECHANISM

William J. Martin, Detroit, Mich., assignor to
Snax Automatic Stores, Inc., Detroit, Mich., a
corporation of Michigan

Application February 16, 1931, Serial No. 515,918
Renewed February 10, 1934

8 Claims. (Cl. 194—97)

My invention relates to a coin control mechanism particularly adapted for use on coin controlled vending machines and the like, and more particularly to a coin control mechanism of the general type disclosed in the co-pending application of Ferdinand Ziganek for slug detecting means, Serial No. 443,755, filed April 12, 1930.

It is essential in the operation of coin controlled vending machines that suitable means be provided for the detection of spurious coins or slugs which may be inserted in the machine in place of the genuine coins upon which the machine is designed to operate. The slug detecting mechanism is, therefore, one of the most important features of any coin control mechanism. It has been found that many so-called slug detector or coin detector mechanisms are not effective in separating the slugs or spurious coins from the genuine coins and frequently permit the operation of the vending machine by such slugs or spurious coins. It also has been found desirable that the slug detecting mechanism used on a coin control of this type should not only separate slugs and spurious coins from the genuine coins so as to prevent the operation of the machine by such coins, but should act to expel such slugs or spurious coins from the machine in order not to impair the operation of the machine when a genuine coin is inserted therein.

Slug detecting mechanisms generally operate on some characteristic of the genuine coin which is not possessed by slugs inserted in the mechanism. One such characteristic of coins has been found to be the raised edge of the milled rim of the coin. It has been found, however, that this characteristic is also possessed by certain slugs which have been used in the operation of vending machines embodying a slug detector which depends upon the raised rim of the coin to separate the genuine coin from a slug.

Slug detecting mechanisms also should be so constructed as to be readily installed in various types of coin controlled vending machines. It is essential, therefore, that such devices be of a size and shape which will not require too much space in the vending machine.

Mechanical simplicity and positive action are essential in coin controls of this type. Thus the elimination of excess parts in such a control and the provision of a mechanism which positively locks the coin controlled vending machine at all times except when a proper coin has been placed in the machine, are improvements much to be desired in mechanisms of this type.

It is, therefore, an object of the present inven-

tion to provide a coin control mechanism which is accurate in its operation and which may be readily installed in a coin controlled vending machine.

It is a further object of the present invention to provide a coin control mechanism which will operate only on genuine coins of the proper predetermined denomination and which will separate slugs or coins of improper denominations from proper coins; and which in addition will expel such slugs or such coins of improper denominations from the machine, thus leaving the machine to which it is attached unimpaired for subsequent operations with proper coins.

These, and various other objects, features of arrangement, construction and operation, are plainly shown and described and will be best understood by reference to the accompanying drawings showing a preferred embodiment of my invention, in which:

Fig. 1 is a front plan view of a coin control mechanism embodying my invention;

Fig. 2 is a fragmentary view in side elevation partially in cross section taken on the line 2—2 of Fig. 1;

Fig. 3 is a fragmentary enlarged view in cross section taken on the line 3—3 of Fig. 1;

Fig. 4 is a cross sectional view in side elevation taken on the line 4—4 of Fig. 1;

Fig. 5 is a fragmentary plan view of the rear of the coin control shown in Fig. 1;

Fig. 6 is a fragmentary sectional view taken on the line 6—6 of Fig. 5;

Fig. 7 is a view in cross section taken on the line 7—7 of Fig. 1.

Similar reference numerals refer to similar parts throughout the several views.

Referring more in detail to the drawings, 8 designates a plate upon which is mounted the coin control mechanism embodying my invention, said plate 8 being of suitable size and shape for mounting in a coin controlled vending machine (not shown). The plate 8 carries a coin receiving chute 9 and slug expelling chutes 10 and 11. A coin chute 12 is provided and communicates with the coin receiving chute 9. An arcuate slot 13 extends through the faces of the coin chutes 9 and 12. One end of the coin chute 12 is adjacent the coin lock 14 secured to the rotatable operating shaft 15 of the vending machine (not shown).

Mounted on the slug expelling chute 10 is a slidably carrier member 16, to which is secured a projecting member 17, a pivoted lever 18 and an upwardly extending finger 19. Pivoted

110

mounted on the coin chute 10 is a pivoted lever 20 having an operating slot 21 contacting with the projecting member 17 mounted on the slideable member 16. A coin detecting point 22 is 5 mounted on the pivoted lever 20 and moves in the arcuate slot 13. Also secured to the slug expelling chute 10 is a track member 23, having raised portions 24 adjacent each end which contact with a depressed portion 25 in the lever 20. 10 The lever 20 pivots about the point 26 secured to the slug expelling chute 10 and is pressed by a spring 27 (Fig. 4) which yieldingly presses the lever 20 toward the coin chute 10.

Pivoted on the slideable member 16 is 15 a swinging latch member 28 yieldingly held in the position shown in Fig. 1 by a spring 29 secured to the slideable member 16. The swinging latch member 28 contacts with an arm 30 rigidly secured to the coin controlled locking member 14.

20 Separating the upper coin chute 9 from the slug expelling chute 10 is a pivoted gate member 31 (Figs. 4 and 5), which is attached to a pivoted link 32, which is connected with the pivoted lever 18 secured to the slideable member 16. A 25 beveled point 33, mounted on a flat spring 34 (Fig. 4) moves through an opening 35 in the wall of the coin chute 9 and is mounted adjacent the gate 31 and the coin detecting point 22. The upwardly extending finger 19, secured to the slideable member 16, contacts with the spring 34 and acts to 30 control the operation of the beveled point 33.

The slug expelling chute 11 (Fig. 4) communicates with the interior of the coin receiving chute 9. An opening 36 is provided in the wall of the coin chute 9 to permit coins or slugs to pass from the interior of the coin chute 9 to the slug expelling chute 11, the opening 36 being of such a size that coins or slugs having a smaller diameter than the coins upon which the device is intended to operate will fall through the opening 36 and directly into the slug expelling chute 11, without necessitating any operation of the machine.

45 The coin lock 14 may be of any conventional type, one of which is here shown and which comprises a plate 37 on which is formed a coin pocket 38 (Fig. 2). A back plate 39 has ratchets 40, which are engaged by the spring pressed pawl 41 secured to the back plate 8. A pivoted locking dog 42 is mounted on the plate 8, and a spring 43 and a stop 44 are secured to the back plate 8 and act to hold the locking dog 42 in the position shown in Fig. 1. The coin controlled locking member 14 is secured to the operating shaft 15 of the vending machine (not shown). A flat coil spring 45 is placed at the rear of the back plate 8 and is attached to the operating shaft 15 and acts to return the coin controlled locking member 14, and the associated slug detecting mechanism, to the position shown in Fig. 1 after the machine has been operated.

50 As shown in Fig. 3, the coin detecting point 22 is secured to the pivoted lever 20 by means of lock nuts 46 engaging the screw threaded shank portion 47 of the point 22. In the embodiment of my invention here shown, the coin detecting point 22 is formed with a 15° angle tapering end portion 48, having a flat end 49. It has been found desirable that the end 49 should not be a sharp point and that the end operates more satisfactorily if there is a flat surface of approximately 0.025 inches in diameter. It has been found that these dimensions permit the coin detecting point 22 to contact with a coin at about $\frac{3}{32}$ of an inch

from the raised edge portion and so insure more perfect operation of the device.

While it has been found that the device embodying my invention will operate as shown in the various views, it is desirable that it be mounted in a machine at a slight angle instead of vertically as shown in Fig. 4. This permits the improper coins or slugs to drop more readily through the opening 36 and into the slug expelling chute 11.

80 The operation of my invention is as follows: Assuming that I have a coin control embodying my invention designed for operating only on five-cent pieces, and assuming that a proper five-cent piece has been inserted in the machine and drops into the coin chute 9, the coin falls through the coin chute 9 and is held by the pivoted gate 31. The person operating the machine turns the proper mechanism for rotating the shaft 15. The mechanism shown is such that a partial rotation of the shaft 15 is permitted without operating the machine and without causing the coin released locking member 14 to contact with the locking dog 42.

85 Upon rotation of the shaft 15, the coin lock 14 is rotated and causes the arm 30 to contact with the swinging latch 28 and move the slideable member 16. The movement of the slideable member 16 moves the projecting member 17 in the slot 21 in the pivoted lever 20 and causes the lever 20 to pivot about the pivot point 26. This movement of the pivoted lever 20 moves the lever so that the depressed portion 25 is moved from the raised portion 24 of the track 23. This permits the coin detecting point 22 to move inwardly and against the coin held by the gate 31. This same movement of the slideable member 16 is transmitted through the upwardly projecting finger 19 and releases the spring 34, which permits the beveled point 33 to contact with the coin on the side opposite the coin detecting point 22. Continued movement of the slideable member 16 in the upward direction by the rotation of the shaft 15, as above described, causes the coin detecting point 22 to be moved by the lever 20 in the curved slot 13, and the coin which has been assumed to have been inserted in the machine being a genuine five-cent piece, the point 22 contacts with the rim of the coin and moves it into the coin chute 12.

90 When the coin has been moved sufficiently to fall into the coin chute 12, the depressed portion 25 of the lever 20 contacts with another of the raised portions 24 of the track 23, causing the point 22 to be raised and the coin dropped into the coin chute 12, from which it is free to roll into the coin pocket 38 of the coin controlled locking member 14. When the slideable member 16 has moved to a position which permits the point 22 to release the coin, the pivoted gate 31 has been caused to swing downwardly so as to leave the mouth of the slug expelling chute 10 open. This same movement of the slideable member 16 has caused the upwardly extending finger 19 to again contact with the spring 34 and to pull the beveled point 33 out of the coin chute 9.

95 When the coin has thus been deposited in the coin controlled locking member 14, the coin controlled locking member 14 has been so rotated that the locking dog 42 will contact with the top of the coin which has been deposited in the coin pocket 38 and permit the full rotation of the coin controlled locking member 14. The member 30 secured to the coin controlled locking member 14 causes the swinging latch 28 to push against the spring 29 and is allowed to swing sufficiently to 100

permit the member 30 to slip past the latch 28 and permit the further rotation of the shaft 15 and the coin controlled locking member 14.

Upon rotation of the shaft 15 sufficiently to operate the machine, the spring 45 is compressed and acts to return the shaft 15 and the coin controlled lock 14 to the position shown in Fig. 1. As the coin controlled lock 14 is rotated in a counter clockwise direction by means of the rotation of the shaft 15, due to the action of the spring 45, the member 30 contacts with the spring pressed latch 28 and is permitted to slip by the spring pressed latch 28 to a projecting portion on the slideable member 16 and causes the slideable member 16 to move downwardly and to positively restore all of the parts to the position shown in Fig. 1.

The dimensions of the coin receiving chute 9 are such that a coin or slug larger than a predetermined coin cannot be inserted in the chute 9.

If, however, a coin or a slug of a smaller diameter than the predetermined coin is inserted in the machine, such a coin or slug will drop through the opening 36 and into the slug expelling chute 11, from which it will pass out of the machine without having passed through the slug detecting mechanism.

If, however, a coin or a slug of the same size as a predetermined coin is dropped into the machine, it will be held by the pivoted gate 31 the same as the genuine coin, as above described. If such a coin or slug is smooth and has no rim, it will not be caught by the point 22 and conveyed into the chute 12 by the movement of the slideable member 16, as above described. However, upon the rotation of the shaft 15 and the movement of the slideable member 16, as above described, the coin conveying point 22 will be moved in the slot 13 but will not carry such a coin with it. Upon opening of the gate 31, as above described, such a coin or slug drops through the slug expelling chute 10 and out of the machine.

One form of slug which has been used to some extent has a raised rim around its outer edge and an opening in its center portion. Such a slug would fall through the coin chute 9 and be held by the gate 31 the same as a genuine coin. Such a slug having a raised rim, the coin conveying point 22 would contact with the rim and tend to convey it into the coin chute 12. The movement of the slideable member 16, however, releases the spring 34, which permits the beveled point 33 to move toward the inside of the chute at the same time that the coin conveying point 22 contacts with the slug. The beveled point 33 enters the opening in the slug and prevents the conveying of such a slug by the point 22 into the chute 12. The movement of the slideable member 16 in the upward direction, as above described, causes a raising of the spring 34 and the removal of the point 33 from inside of the coin chute 9 after the coin conveying point 22 has passed beyond the edge of the coin, which movement releases the slug theretofore held by the point 33 and permits it to drop into the slug expelling chute 10 and out of the machine.

In the operation of devices of this type it was found that if a lead or other relatively soft metal slug was inserted in the machine and was of the proper size to reach the pivoted gate 31, that such a coin frequently would be conveyed by the coin conveying point 22, particularly if the point on the coin conveying point 22 was sufficiently sharp to scratch the surface of the metal. It also was found that a sharp point on the coin con-

veying point 22 would tend to engage a coin and cause the coin to rotate about that point. The additional friction between the coin and the point and the coin and the back of the coin chute thus created frequently prevented satisfactory operation of the machine. These objections were found to be overcome if the end of the coin conveying point 22 was slightly flattened as shown by the point 49 (Fig. 3). This slightly flattened point 49 is such that it does not scratch a soft metal slug and will slip over such a slug without conveying the slug to the coin chute 12. The slightly flattened point 49 also tends to slip over the surface of the coin and engages the raised rim on the coin on the beveled portion 48. The movement of the beveled portion 48 on the interior of the rim on the coin causes the coin to roll into the coin chute 12 as it is moved by the conveying point 22.

From the foregoing it will be apparent that I have shown a coin control device embodying my invention which is positive in its operation and which separates the slugs or improper coins from the genuine coins and passes such slugs or coins into chutes from which they are taken out of the vending machine and leaves the coin control mechanism unimpaired for operation with a proper coin.

While I have illustrated a preferred embodiment of my invention, many modifications may be made without departing from the spirit of the invention, and I do not wish to be limited to the precise details of construction as herein set forth, but desire to avail myself of all changes within the scope of the appended claims.

Having thus described my invention, what I claim is new and desire to secure by Letters Patent of the United States, is:

1. A control for coin operated machines having operating means, including coin released locking means secured to said operating means, and slug detecting means operatively connected with said coin released locking means, and including a coin chute, having a coin receiving portion, a second coin chute communicating with said coin receiving portion of said coin chute and said coin released locking means, means for propelling proper coins from said coin receiving portion to said second coin chute, an expelling chute communicating with said coin receiving portion of said coin chute, movable means separating said expelling chute from said coin receiving portion and said coin chute, and means for operating said last named means whereby a coin or slug not moved into said second coin chute is dropped into said slug expelling chute, and means for returning said coin released locking means and said slug detecting means to their original positions after operation of said operating means.

2. A control for coin operated machines having operating means, coin released locking means secured to said operating means, slug detecting means operatively connected with said coin released locking means and including a central coin chute, movable means dividing said central coin chute into a coin receiving portion and a slug expelling portion, means for conveying coins from said coin receiving portion of said central coin chute to said coin released locking means and including a pivoted lever secured to said central coin chute, and a coin conveying point secured to said pivoted lever, means for operating said means for dividing said central coin chute whereby coins not conveyed from said coin receiving portion will drop into said slug expelling portion, and

means for returning said coin released locking means and said slug detecting means to their original positions after operation of said operating means.

- 5 3. A control for coin operated machines having operating means, and including coin released locking means secured to said operating means, slug detecting means operatively connected with said coin released locking means and including a central coin chute, a gate dividing said central coin chute into a coin receiving portion and a slug expelling portion, means for conveying coins from said coin receiving portion of said central coin chute to said coin released locking means,
- 10 15 said conveying means including a pivoted lever secured to said central chute and a coin conveying point secured to said pivoted lever, means actuated by said operating means for moving said lever and said coin conveying point, and means secured to said means for moving said lever whereby said gate is opened after movement of said lever, and means for returning said coin released locking means and said slug detecting means to their original positions after operation of said operating means.

- 20 25 4. A control for coin operated machines having operating means, and including coin released locking means secured to said operating means, slug detecting means operatively connected with said coin released locking means and including a central coin chute, a gate dividing said central coin chute into a coin receiving portion and a slug expelling portion, means for conveying coins from said coin receiving portion of said central coin chute to said coin released locking means, said conveying means including a pivoted lever secured to said central chute and a coin conveying point secured to said pivoted lever, and a side chute communicating with said central chute, means actuated by said operating means for moving said lever and said coin conveying point in the direction of said side chute, means secured to said means for moving said lever for opening said gate after movement of said lever, and means controlled by said means for moving said lever whereby coins or slugs having openings therein are prevented from being delivered to said coin released locking means by said coin conveying means, and means for returning said coin released locking means and said slug detecting means to their original positions after operation of said operating means.
